SPACE HEATER

Wesley J. Snyder, Mathias Roth, James Dillingham, and Kenneth S. Jenson, Wisconsin Rapids, Wis., assignors to Preway, Inc., a corporation of Wisconsin

Application June 1, 1954, Serial No. 433,332

8 Claims. (Cl. 126—93)

This invention relates to a new and improved space heater which may be used as either a gravity air or forced draft type space heater by rearrangement and addition of parts which may be assembled without error.

In the past, the attachments used for such modifications were of a type which the average purchaser, unskilled in mechanical things, might improperly assemble into a device which although possibly operable, might also, because of hazardous function, result in subsequent harm to the purchaser or the various parts of the space heater and attachments.

To remedy the possibility of improper assembly we have provided a space heater constructed and arranged with new and improved means which allow a purchaser to make modifications substantially without possibility of error. Accordingly, the invention relates more particularly to a space heater which can be easily and properly modified substantially without possibility of mistake for use as a forced or gravity circulating type air heater and for use with either an integral or remote stationary type fuel tank.

Another object of the invention is to provide a space heater having parts which must necessarily be removed or conversely installed before the space heater can be operably modified and which can only be assembled in a certain proper sequence and position.

Another object of the invention is to provide a heater embodying a lower backplate provided with a pair of angle bars and operable as a partial closure member for the lower part of the opening in the back of the cabinet, a blower unit provided with hooks for use with hook holes in the angles, the construction and arrangement being such that the blower unit cannot be assembled with the cabinet until the lower backplate and angles have been secured in proper position.

Yet another object of the invention is to provide a heater as described above with a lower backplate operable without the angle bars and secured to the cabinet back by suitable means, the blower unit hooks being received in holes in the cabinet adjacent either side of the opening which cannot receive the hooks before removal of a shield and upper backplate utilized when the heater is used as a gravity air flow heater.

Yet another object of the invention is to provide frame means for use with the construction as described above wherein a fuel tank may be securely supported behind the blower unit, the construction and arrangement being such that the fuel tank cannot be operably mounted behind the blower unit without the use of the upper backplate which acts as a heat radiation protecting means for the fuel tank.

Other and further objects of the invention will be readily apparent from the following description and drawings in which:

Fig. 1 is a rear elevational view of a form of the invention showing a blower unit operably associated with the cabinet to adapt the heater for use as a forced air heater, the blower unit having a portion cut away to illustrate a filter and grill associated therewith;

Fig. 1A is a fragmentary elevational view of a portion of the means operable for supporting the blower unit in position and illustrating the hook hole in the lower backplate right hand angle bar;

2

Fig. 1B is a fragmentary side elevational view looking at the right hand side of the structure illustrated in Fig. 1A;

Fig. 2 is a fragmentary sectional view taken along line 2—2 of Fig. 1 illustrating the relationship between a portion of the lower backplate and associated angle bars, the blower unit, the adjacent portions of the back side of the cabinet and means for securing the blower unit in position;

Fig. 3 is a fragmentary right-hand side elevational view of the form of the invention illustrated in Fig. 1, but showing the blower unit mounted to the cabinet without the use of the lower back panel angle bars and using instead hooks operable with holes in the cabinet back;

Fig. 4 is a fragmentary rear elevational view of the structure illustrated in Fig. 3;

Fig. 5 is a top plan view of a form of the invention and illustrating the heater as adapted for use as a forced air type with frame means supporting a portable fuel tank behind the blower unit; and,

Fig. 6 is a side elevational view of the form of the invention illustrated in Fig. 5 with a portion of the blower unit and adjacent portion of the cabinet broken away.

While we have shown in the drawings and shall herein describe in detail a preferred embodiment of the invention, it is to be understood that we do not hereby intend to limit the invention to the specific forms disclosed. It is contemplated that various changes may be made by those skilled in the art without departing from the spirit and scope of the invention as expressed in the appended claims.

The space heater of this invention comprises a casing or cabinet A having a front wall 10 rising from a floor shield plate 11 and joining with side walls 12 interconnected by a back wall 13 to support a top wall 14. The cabinet top is provided with a grill which may comprise a plurality of spaced apart forwardly-inclined louvres 15, the upper portion of the front wall being provided with a plurality of louvres 16. A door 17 is provided in the front wall of the cabinet for access through the cabinet to a combustion chamber in the form of a drum B supported from the bottom of the cabinet in a spaced relation from the cabinet walls. A flue pipe 18 is connected to the rear of the drum and extends through the back wall of the cabinet above a rectangular air opening 19 beginning a slight distance below the flue and extending to the floor shield plate of the cabinet. The opening is provided with an inwardly-extending vertical flange 20 running the height of the opening, adjacent each side thereof. Each flange is pierced with two threaded holes 21 for use with a forced air modification of the heater. A plurality of leveler bolts 24, threadably received in the floor shield 11, adjustably support the cabinet on a floor surface. It is contemplated that a suitable burner and associated mechanical means normally used in a heater of this type may be utilized and for a disclosure of one type burner and associated mechanical means reference is directed to Patent No. 2,576,685 entitled "Forced Air Circulation Combustion Type Space Heater," issued November 27, 1951, to K. S. Jenson.

A plurality of possible modifications are illustrated by the drawings: a forced air type space heater shown without the use of an integral fuel tank (Figs. 1, 3 and 4), the Figs. 3 and 4 illustrating a modified means for supporting the blower unit in position on the back wall of the cabinet; and the forced air type heater adapted for use with an integral fuel tank (Figs. 5 and 6) and illustrating a further modified means for supporting the blower unit in position.

There are two sets of spaced screw passing unthreaded

holes in the cabinet back adjacent each side of the opening 19. Each set comprises two holes, one hole 32 of each set being of greater diameter than the other hole 33 of the set so as to be adaptable for receiving the hooks of a blower unit in a forced draft modification.

A tank may then be operably connected to the heater by any suitable conduit 46 (Fig. 3) removably secured at one end to the tank and at the other end to a constant level valve 46a which connects with a burner inlet pipe 47 operable with the burner mechanism of the heat drum.

The forced air modification illustrated in Figs. 1 and 2 embodies the use of a substantially rectangular lower backplate or cover plate 50 provided with spaced openings 51, 52 and 53 and carrying a vertical angle bar 54 at each end attached to the plate 50 by any suitable means. The plate is positioned on the outside of the cabinet back across the lower portion of opening 19 and its upper edge defines the lower extremity of the remaining air opening. Each of the angle bars 54 is provided with a flange 58 normal to the casing back and positioned in the air opening overlying cabinet flanges 20. The angle flanges are provided with unthreaded holes 58' (Fig. 2) which register with threaded holes 21 in the cabinet flanges for receiving screws 59 to secure the lower backplate in position, the arrangement being such that the angle flange holes will not register with holes 21 if an attempt is made to secure the lower backplate in an upside-down position. Each of the angles is provided with a flange 60 extending in a plane parallel with the backside of the cabinet and overlying and closing the cabinet holes 32 and 33 as a safety measure against attempted repositioning of an upper backplate and shield utilized when the heater is used as a gravity air flow heater.

A blower unit 61 embodying a closed casing 62 of a size to completely enclose the remaining air opening, a fan and motor 63, a front plate 64 and a rear grill 65 protecting a filter 66, is hung adjacent the back of the cabinet by hooks 67 which are pivotally mounted to the blower casing at 68 and received in protruding slots 69 and pockets 70 provided in each flange 60 as best illustrated in Fig. 1. The hooks are pivoted on each side of the blower casing at a point spaced rearwardly from the cabinet back and extend upwardly and toward the back so that the weight of the blower keeps it in place against the cabinet back.

If a remote stationary fuel tank (not shown) is to be utilized, the conduit 46 may be extended to the tank. The center opening 52 receives the burner inlet pipe when one burner and one heating drum is used. When a twin-type heater having two burners and two drums is used, the two inlet pipes pass through openings 51 and 53.

The Figs. 3 and 4 illustrate a modified method for hooking the blower unit in position without the use of angle bars 54. The lower backplate 50 is secured in position by any suitable means as by stove bolts through unthreaded holes 76 and 77 in the backplate and cabinet, respectively, and the blower unit hung in place by elongated hooks 67' inserted through the large cabinet holes 32, one hook being slightly longer than the other because of the vertical offset positioning of holes 32 so that the blower unit will not hang at an angle. This construction also necessitates removal of a shield and upper backplate as the holes in each shield bracket registering with the enlarged cabinet holes are of smaller diameter and block entry of the hooks when the shield and upper backplate are in position when the heater is used as a gravity air flow heater. In either modification, the blower hooks provide adequate mounting means for the blower.

If a remote fuel tank is not accessible, the heater construction illustrated in Figs. 1, 3 and 4 may be further modified for use with integral fuel tank. As shown in Figs. 5 and 6, the fuel tank is supported by a bracket embodying an open box-like frame comprising horizontal

upper members 78 connected by an upper cross member 79 and supported at each side by vertical members 80 (one of which is shown) which are joined by a lower cross member (not shown) and are each provided with a bottom member 81 having a floor supporting portion 82. Each of the upper members 78 carries a vertical flange 83 provided with threaded holes registering with unthreaded holes 84 in the back side of the cabinet for receiving screws 85 to secure the upper portion of the bracket to the cabinet back. Bottom members 81 are secured to the rearwardly-extending portion of the floor shield by screws 86 threadably received in the floor shield. The integral tank supporting frame is of open, flexible construction so that regardless of the adjustment given to leveler bolts 24 the floor supporting portions 82 of the frame will always rest upon the floor. An upper backplate 37 is then secured by any suitable means to the rear portion of the fuel tank frame and the fuel tank 45 is hung to the upper backplate by bracket hooks 44. A conduit 87 may then be secured at one end to the fuel tank and at the other end to regulating valve 46a and the space heater is operably assembled.

If it is desired to use the construction illustrated in Figs. 5 and 6 as a gravity air heater, the blower unit may be easily disengaged from the cabinet without disturbing the frame and the construction is operable for such use, the upper backplate thereafter serving to protect the integral fuel tank from excessive heat radiation.

We claim:

1. A heater provided with a casing having a flat back with a substantially rectangular opening therein comprising vertical inwardly-extending flanges along opposite sides of the opening each provided with spaced threaded holes, means defining unthreaded holes in the casing back adjacent the opposite sides of the opening for receiving fastening devices operable with a shield plate and backplate when the heater is used as a gravity air flow heater, heating elements in said casing provided with a fuel supply pipe extending out through the lower portion of the air opening, a cover plate extending across a lower portion of the rectangular opening and having a bottom edge notch fitting over said supply pipe, the top of said cover plate defining the lower limits of an air opening, a vertically-extending angle bar secured to each end of the cover plate each of said angle bars having a flange normal to the back of the casing and positioned within said air opening, there being holes in said angle flange registering with the threaded holes in the vertical cabinet flanges to receive threaded means for securing the cover plate to the casing, a second flange portion on each of said angle bars overlying and closing the holes adjacent the sides of the air opening in said casing, said second flange portion having hook holes therein, a blower unit having a casing shaped to cover the air opening, hooks pivotally mounted to said blower casing and extending upwardly and toward said heater casing for engagement with the hook holes for fastening said unit operably to the heater casing, a flexible open box-like bracket frame positioned around said blower unit and having a portion resting on a surface supporting the heater casing, means for securing the bracket to the heater casing, the backplate being releasably secured to said rear frame portion behind the blower unit, a fuel tank, and a pair of hooks engageable with apertures in the backplate for hanging said fuel tank in operable position against the backplate.
2. A heater with a casing having a back with an opening therein comprising, inwardly-extending flanges along opposite sides of the opening each provided with spaced threaded holes, means defining unthreaded holes in the casing back along the opposite sides of the opening for receiving fastening devices operable with a shield plate and backplate when the heater is used as a gravity air flow heater, a cover plate extending across the lower portion of the rectangular opening with its upper extremity

defining the lower limits of an air opening, an angle bar secured to each end of the cover plate, each of said angle bars having a flange normal to the back of the casing and positioned within said air opening, there being holes in said angle flange registering with the threaded holes in the cabinet flanges to receive screws for securing the cover plate in position, a second flange portion on each of said angle bars overlying and closing the holes along the sides of the air opening in said casing, said second flange portions having hook holes therein, a blower unit having a casing shaped to cover the air opening, hooks pivotally mounted to said blower casing and extending upwardly and toward said heater casing for engagement with the hook holes for fastening said unit operably to the heater casing, a flexible open bracket frame positioned around said blower unit and having a portion resting on a surface supporting the heater casing, means for securing the bracket to the heater casing, the backplate being releasably secured to said rear frame portion behind the blower unit, a fuel tank, and means for releasably securing said fuel tank in operable position against the backplate.

3. A heater with a casing having a back with an opening therein comprising; vertical inwardly-extending casing flanges along opposite sides of the opening each provided with spaced threaded holes, means defining spaced unthreaded holes in the casing back along the opposite sides of the opening for receiving fastening devices operable with a shield plate and backplate when the heater is used as a gravity air flow heater, a coverplate extending across the lower portion of the opening with its upper extremity defining the lower limits of an air opening, a vertically-extending angle bar secured to each end of the coverplate, each of said angle bars having a flange normal to the back of the casing and positioned within said air opening, there being holes in said angle flange registering with the threaded holes in the vertical casing flanges to receive threaded devices for securing the coverplate in position, a second flange portion on each of said angle bars overlying and closing the holes along the sides of the air opening in said casing, each of said second flange portions having a hook hole therein, a blower unit having a casing shaped to cover the air opening above the lower coverplate, hooks pivotally mounted to said blower casing and extending upwardly and toward said heater casing for engagement with the hook holes for fastening said unit operably to the heater casing.

4. A heater with a casing having a back provided with an opening therein comprising; vertical inwardly-extending flanges along opposite sides of the opening each provided with spaced threaded holes, means defining unthreaded holes in the casing back along the opposite side of the opening, a coverplate extending across the lower portion of the opening with its upper extremity defining the lower limits of an air opening, a vertically-extending angle bar secured to each end of the coverplate, each of said angle bars having a flange normal to the back of the casing and positioned within said air opening, there being holes in said angle flange registering with the threaded holes in the vertical casing flanges to receive fastening devices for securing the coverplate in position on the outside of the casing back, a second flange portion on each of said angle bars overlying and closing the holes along the sides of the air opening in said casing, a flexible open bracket frame positioned around said air opening allowing for positioning of a blower unit across the air opening and having a portion resting on a surface supporting the heater casing, means for securing the bracket to the heater casing, a supporting member releasably secured to said rear frame portion, a fuel tank, and means operable for releasably securing said fuel tank in operable position against the supporting member.

5. A heater with a casing having a back with an opening therein comprising; means defining unthreaded holes in the casing adjacent the opposite sides of the opening

for receiving fastening devices operable with a shield plate and backplate when the heater is used as a gravity air flow heater, a coverplate extending across a lower portion of the rectangular opening with its upper extremity defining the lower limits of an air opening, means releasably securing the coverplate in position on the outside of the casing back, a blower unit having a casing shaped to cover the air opening, hooks pivotably mounted to said blower casing and extending upwardly and toward said heater casing for engagement with one of said unthreaded holes in the casing on either side of the opening for mounting the blower unit to the heater casing, a flexible open bracket frame positioned around the blower unit and having a portion resting on a surface supporting the heater casing, means for securing the bracket to the heater casing, the backplate being releasably secured to said rear frame portion behind the blower unit, a fuel tank, and means for releasably securing the fuel tank in operable position against the backplate.

20 6. A heater with a casing having a back with an opening therein comprising; vertical inwardly-extending flanges along opposite sides of the opening each provided with spaced threaded holes, means defining spaced unthreaded holes in the casing adjacent the opposite sides of the opening for receiving fastening devices operable with a shield plate and backplate when the heater is used as a gravity air flow heater, a cover member extending across a lower portion of the opening with its upper extremity defining the lower limits of an air opening, a vertically-extending member secured to each end of the cover member, each of said members having a flange normal to the back of the casing and positioned within said air opening, there being holes in said flange registering with the threaded holes in the vertical casing flanges to receive threaded devices for securing the cover member in position on the outside of the casing back, a blower unit having a casing shaped to cover the air opening, and means pivotably mounted to said blower casing for engagement with one of said unthreaded holes in the heater casing on either side of the air opening for releasably securing said blower unit to the casing in operable position with the air opening.

7. A heater with a casing having a back with an opening therein comprising; a cover member extending across a lower portion of the opening with its upper extremity defining the lower limits of an air opening, means releasably securing the cover plate in position on the outside of the casing back, means defining an unthreaded hole adjacent each side of the opening and adapted for receiving means operable for releasably securing a blower unit across the air opening, a flexible open bracket frame having a portion resting on a surface supporting the heater casing, means for securing the bracket to the heater casing back, and means releasably securing a portable fuel tank to a portion of the bracket frame in operable relation with the heater.

8. A heater with a casing having a back with an opening therein comprising; means defining a hook hole in the casing back adjacent each side of the opening, a cover member extending across the lower portion of the opening with its upper extremity defining the lower limits of an air opening, means for securing the cover plate in position on the outside of the casing back, a blower unit having a casing shaped to cover the air opening, and hooks pivotably mounted to said blower casing and extending upwardly and toward said heater casing for engagement with the hook holes for fastening said unit in operable position with the air opening and to the casing back.
